DESIGN FOR A CIGARETTE HOLDER

Matthew R. Grandon, Beverly Hills, Calif.

Application September 24, 1945, Serial No. 122,298

Term of patent 14 years

(Cl. D85—8)

To all whom it may concern:

Be it known that I, Matthew R. Grandon, a citizen of the United States, residing at Beverly Hills, in the county of Los Angeles and State of California, have invented a new, original, and ornamental Design for a Cigarette Holder, of which the following is a specification, reference being had to the accompanying drawing, forming a part thereof.

I claim:

The ornamental design for a cigarette holder, as shown.

MATTHEW R. GRANDON.
